CHANGEABLE INDICATOR SIGN

John R. Harding, Waynesboro, Va., assignor to Acme Visible Records, Inc., Crozet, Va., a corporation of Delaware

Filed Jan. 6, 1964, Ser. No. 78,083

Term of patent 14 years

(Cl. D1—12)

Fig. 4

FIG. 1 is a front elevational view of a changeable indicator sign showing my new design.

FIG. 2 is another front elevational view thereof showing the sliding panel in a different position from that illustrated in FIG. 1.

FIG. 3 is another front elevational view thereof showing the sliding panel in a third position; and

FIG. 4 is a side elevational view thereof.

The broken lines depicting placement of indicia on the changeable indicator sign are for illustrative purposes only.

I claim:

The ornamental design for a changeable indicator sign, substantially as shown and described.
